[57] CLAIM

The ornamental design for a loudspeaker wall support, as shown and described.

DESCRIPTION

FIG. 1 is a perspective view of a loudspeaker wall support showing my new design;

FIG. 2 is a typical end view thereof when the ends are aligned to lie in parallel planes, the opposite end view being identical thereto; and,

FIG. 3 is a side view thereof when the ends are aligned to lie in parallel planes, the opposite side view, the top view, and the bottom view being identical thereto.

FIG. 1

FIG. 2

FIG. 3
